(57) **CLAIM**

The ornamental design for an insole for a high heel shoe, as shown and described.

DESCRIPTION

FIG. 1 is a perspective view of an insole for a high heel shoe showing my new design in a condition of use;

FIG. 2 is a front elevational view of FIG. 1;

FIG. 3 is a rear elevational view of FIG. 1;

FIG. 4 is a right-side elevational view of FIG. 1;

FIG. 5 is a left-side elevational view of FIG. 1;

FIG. 6 is a top plan view of FIG. 1;

FIG. 7 is a bottom plan view of FIG. 1;

FIG. 8 is a perspective view thereof, illustrated in a flat configuration;

FIG. 9 is a front elevational view of FIG. 8;

FIG. 10 is a rear elevational view of FIG. 8;

FIG. 11 is a left-side elevational view of FIG. 8;

FIG. 12 is a right-side elevational view of FIG. 8;

FIG. 13 is a top plan view of FIG. 8;

FIG. 14 is a bottom plan view of FIG. 8; and,

FIG. 15 is a cross-sectional view thereof.

The broken lines showing a high heel shoe in FIG. 1 depict environmental matter and form no part of the claimed design.

The remaining broken lines represent portions of the insole for a high heel shoe that form no part of the claimed design.

1 Claim, 14 Drawing Sheets
